UNITED STATES PATENT OFFICE.

ELLERY C. WRIGHT, OF BROCKTON, MASSACHUSETTS.

LAST.

SPECIFICATION forming part of Letters Patent No. 605,768, dated June 14, 1898.

Application filed May 22, 1897. Serial No. 637,657. (No model.)

To all whom it may concern:

Be it known that I, ELLERY C. WRIGHT, of Brockton, in the county of Plymouth and State of Massachusetts, have invented an Improvement 5 in Lasts, of which the following description, in connection with the accompanying drawings, is a specification, like letters on the drawings representing like parts.

In the use of wooden lasts in the manufacture of boots and shoes the lasts are in the various processes through which they pass subjected to great pressure and strain, and to prevent the last from splitting and wearing out too rapidly the hole in the cone of the last, which is entered by a usual last-pin, has been provided with a metallic socket; but this metallic socket in use is frequently forced farther into the last and the strains exerted on the last through the pin and socket frequently split the same, and it is to obviate this liability of splitting the last and of forcing the socket-piece into the body of the last that I have devised the invention herein to be described.

25 My present invention is an improvement on the invention shown in United States Patent No. 398,923, in which a short block is embedded in the last beneath the socket to constitute a laterally-extended bearing therefor. 30 In said patented device, however, the construction is such that the tendency is to bend the block, bringing the pressure solely on that part of the last below the said block and socket, this arrangement in practice often proving insufficient to prevent the settling of the metallic socket, so that the cone of the last or wood portion thereof is unsupported and at once crushes down. Accordingly I have placed a stay beneath the socket, so constructed and arranged that the pressure transmitted thereto by the socket is not taken solely by that part of the last below it, as in said patented device, but is taken by the whole heel part of the last, and to this end 45 I have secured the ends of the stay in the respective sides of the last, so that when the pressure is brought on its intermediate portion by the pressure of the socket, its ends being firmly secured, the stay is put under 50 tensile strain, tending to pull in the sides toward each other, and thereby offering their resistance, in addition to the resistance of the

extended lateral bearing, and enabling the socket much more effectually to maintain its support to the cone of the last.

Figure 1, in side elevation, represents a last embodying this invention; and Fig. 2 is a section in the line x.

The wooden last A, of any usual shape, is bored at its cone a to receive a metallic pin-socket b, which is driven into the said bored hole, leaving the open end of the socket substantially flush with the top of said cone. Preferably before inserting the said socket into the said bore I bore a transverse hole 65 through the last from one to its opposite side beneath the bottom of the bore made for the reception of the said socket, and in this bore I place a stay, which may be made as a bolt c, having at one end a head c', said bolt when 70 in place receiving upon its opposite end a clamping-nut c², or the ends of the said bolt may be upset and headed, preferably over washers. The application of this stay to the last before forcing the socket into the bore 75 made for it obviates splitting the last.

The main object of my invention is to increase the pressure resistance of the last, and to that end I make provision, so that not only will that portion of the last below the stay 80 serve to support the latter, and thereby support the socket or other equivalent pressure-receiving member when the latter rests on the stay or binder or is pressed down onto it, but also the opposite sides of the last will 85 also support the stay, the latter acting as a chord to compress the sides toward each other, being placed under tensile strain by downward pressure at its middle to pull the sides together, thereby adding their resist- 90 ance to that of the last material below the stay. To further increase the binder or truss effect of my stay or pressure-resistance member c, I prefer to provide it with enlarged ends or abutments, as shown, either separate 95 or integral with the bolt c, these abutments being shown at c³ c⁴ countersunk in the last. The bolt or stay c is placed beneath the socket b in the direct descending path of the socket and preferably immediately against the inner end thereof and acts as a combined rest or bottom for the socket and stay or truss for the sides.

Having fully described my invention, what

I claim, and desire to secure by Letters Patent, is—

1. The combination with a last and its socket, of a socket-supporting truss member extending transversely through the last in vertical alignment below said socket, constructed to provide resistance to endwise inward movement of the ends of said truss member thereby to resist transverse depression of said truss member between its ends under the settling tendency of said socket.

2. In a last, having a socket, a pressure-resistance member extending transversely of

and from side to side of the last to constitute a combined support for the bottom of the socket and stay or binder for the sides, each end thereof having a laterally-extended abutment countersunk in the side of the last, substantially as described.

In testimony whereof I have signed my name to this specification in the presence of two subscribing witnesses.

ELLERY C. WRIGHT.
